(57) **CLAIM**

The ornamental design for a lower back support, as shown and described.

DESCRIPTION

FIG. 1 is a perspective view of an embodiment of a garment having the lower back support;

FIG. 2 is a front elevation view of the garment with the lower back support of FIG. 1;

FIG. 3 is a back elevation view of the garment with the lower back support of FIG. 1;

FIG. 4 is left-side elevation view of the garment with the lower back support of FIG. 1, where the right-side elevation view is a mirror image of the left-side;

FIG. 5 is a top plan view of the garment with the lower back support of FIG. 1;

FIG. 6 is bottom plan view of the garment with the lower back support of FIG. 1;

FIG. 7 is a back elevation view of the garment with the lower back support of FIG. 1 showing straps of the lower back support in an extended position;

FIG. 8 is a front elevation view of the garment with the lower back support of FIG. 1 showing straps of the lower back support in an extended position;

FIG. 9 is left-side elevation view of the garment with the lower back support of FIG. 1 showing straps of the lower back support in an extended position, where the right-side elevation view is a mirror image of the left-side;

FIG. 10 is a top elevation view of the garment with the lower back support of FIG. 1 showing straps of the lower back support in an extended position; and,

FIG. 11 is a bottom elevation view of the garment with the lower back support of FIG. 1 showing straps of the lower back support in an extended position.

(Continued)

The broken lines showing a garment depict environment and form no part of the claim. The broken lines within claimed surfaces depict portions of the lower back support and form no part of the claimed design.
